UNITED STATES PATENT OFFICE.

GEORGE A. MORRIS AND OTIS C. BYRD, OF WEBB CITY, OKLAHOMA.

SAND REAMER.

Application filed February 7, 1927. Serial No. 166,500.

This invention relates to a sand reamer for oil and gas wells and the like, the general object of the invention being to provide a tool which has its cutter carrying portion 5 swiveled to another portion, with means for enclosing the swiveled part to prevent the same from being damaged by sand and other foreign matter.

Another object of the invention is to hinge-10 edly connect the lower portion of the tool with the upper portion thereof and to provide a spring for pressing the lower portion outwardly so that the cutters will engage the wall of the well and thus remove sand from the 15 same.

This invention also consists in certain other features of construction and in the combination and arrangement of the several parts, to be hereinafter fully described, illustrated in 20 the accompanying drawings and specifically pointed out in the appended claims.

In describing our invention in detail, reference will be had to the accompanying drawings wherein like characters denote like or 25 corresponding parts throughout the several views, and in which:—

Figure 1 is an elevation of the device showing the cutter carrying portion swung outwardly in dotted lines.

Figure 2 is a view of the upper portion of the tool, the view being taken at rightangles to Figure 1.

Figure 3 is a sectional view through part 35 of the device, showing the hinge and swivel connections.

Figure 4 is a view of one of the cutters.

In these views, 1 indicates the upper section of the tool which is provided with the tapered threaded part 2 which is adapted to 40 engage a threaded socket of a standard drilling tool, this part 1 being provided with a wrench engaging part 3 whereby the threaded part 2 can be screwed or unscrewed from the socket of a drilling tool by a wrench. The 45 lower end of the section 1 is provided with a flattened reduced part 4 which is formed with a long extension 5 at one side thereof. The section 6 of the tool is forked at its upper end, the prongs 7 of which receive the reduced part 50 4 between them and a pin 8 passes through the prongs and the reduced part so that the section 6 is hingedly connected with the section 1. A recess 9 is formed in one side of the section 6 to receive the extension 5 and the said 55 section 6 is also provided with a socket 10 which opens out into the lower part of the re-

cess 9 to receive a coiled spring 11 which engages a seat 12 on the extension 5, this spring acting to move the section 6 to one side by bearing against the extension 5, as 60 shown in dotted lines in Figure 1. When the sections are to be held in alignment, a pin 13 is passed through holes formed in the section 6 and in the extension 5 to prevent movement of the section 6 by the spring 11. 65

The cutter carrying shank 14 is provided with an enlarged top part 15 which is of the same diameter as the section 6 and a stem 16 is connected with the upper part of the enlargement 15 and passes through a threaded 70 bushing 17 which is adapted to be screwed into a socket 18, the walls of which are threaded. The stem is rotatably held in the bushing by means of a nut 19 engaging the threaded upper end of the stem 16, a pin 20 being 75 passed through the upper end of the threaded portion to hold the nut in place. Thus the shank is swiveled to the section 6 and the swiveled parts are enclosed so that sand can- 80 not reach them.

The shank 14 is of square shape in cross section and it is provided with the undercut notches 21 to receive the upper ends of the cutters 22 which are held in place by the rivets 23, each rivet holding a pair of cutters 85 to the shanks. These cutters are of angle shape, as shown in Figure 4, so that their cutting portions will be located a consider- able distance from the shank.

As will be seen, when this device is attached 90 to a drilling tool and lowered in the well, when the tool is rotated the cutters will engage the sides of the well and free the same of sand and the like and as the spring holds the cutter carrying part of the device at an angle 95 from the vertical, the portion of the well engaged by the device will be enlarged.

It is thought from the foregoing description that the advantages and novel features of our invention will be readily apparent. 100

We desire it to be understood that we may make changes in the construction and in the combination and arrangement of the several parts, provided that such changes fall within the scope of the appended claims. 105

What we claim is:—

1. A device of the class described comprising two sections normally arranged in end to end relation, one section including a reduced apertured extension depending from 110 one end, the adjacent end of the other section being bifurcated to receive said exten-

sion upon which it is pivotally mounted, said second mentioned section being longitudinally slotted for a portion of its length, an arm depending from the first mentioned section 5 and received by said slot, expandible means located between the arm and the second mentioned section for moving the latter to an angular position with relation to the first mentioned section, means for holding said 10 second mentioned section in end to end relation with the first mentioned section, and a cutter carrying shank detachably connected with the lower end of the second mentioned section.

15 2. A device of the character described comprising two sections arranged in end to end relation, a reduced extension depending from the lower end of the upper section, a relatively long arm depending from the same 20 section at one side of the extension, the sec-

ond section having its upper end bifurcated to receive the extension upon which it is pivotally mounted, and formed with a longitudinal slot to receive said arm, an expandible element arranged within the second mentioned section and bearing against said arm whereby the second mentioned section is moved to a position at an inclination to the first mentioned section, means for holding said sections in end to end relation against 25 the influence of the expandible member, said second mentioned section having a threaded bore in its lower end, a bushing threaded in said bore, and a cutter carrying shank including a reduced portion swiveled in said bushing.

In testimony whereof we affix our signatures.

GEORGE A. MORRIS.
OTIS C. BYRD.
